UNITED STATES PATENT OFFICE.

SILVIO MAGATON, OF NEW YORK, N. Y.

TEMPERATURE ALARM DEVICE.

1,410,490.

Specification of Letters Patent. Patented Mar. 21, 1922.

Application filed February 8, 1921. Serial No. 443,464.

To all whom it may concern:

Be it known that I, SILVIO MAGATON, a citizen of Italy, residing in the city of New York, county of New York, borough of Manhattan, and State of New York, have invented certain new and useful Improvements in Temperature Alarm Devices, of which the following is a full, clear, and exact specification.

10 My invention relates to temperature alarm devices and refers particularly to thermometer control devices.

One object of my invention is a device whereby an alarm will be sounded by an increase of temperature above a predetermined point.

Another object of my invention is a device whereby an alarm will be sounded continuously until manually interrupted.

20 My device has numerous applications among which I specifically mention its use as a fire alarm and as a means of notification when the temperature within a chimney, or flue, exceeds a predetermined temperature.

25 My device depends for its operativeness upon the increase of temperature as registered by a mercury, or other liquid, thermometer.

The objects and advantages of my device 30 will be evident upon a consideration of my drawings, specification and claims.

In the particular form of the device of my invention, shown in the accompanying drawings, similar parts are designated by

35 similar numerals.

Figure 1 is a side elevation, partly in section and partly broken away for clearness of disclosure.

Figure 2 is a section through the line 2—2 40 of Figure 1.

Figure 3 is a broken enlarged elevation of a portion of the make and brake device showing the device in a completed circuit position.

45 The particular form of the device of my invention, shown in the accompanying drawings, comprises a box having the back 10, the annular side 11 and the front annular member 12. The foraminous side 11 has a series 50 of openings 13, 13. The front 12 carries a plate of glass 14, and is hinged to the side 11 at 15. A hinged member 16 is fixedly attached to the side 11 and the opening 17 is capable of placement over the ring staple

18, carried by the extension 19 of the front 55 12, thus allowing the insertion of a pad lock 20 whereby the front may be locked in a closed position. A supporting member 21 extends transversely across the box and is fixedly attached to the side 11. The back 60 has an inwardly extended portion 22. The two threaded pointed members 23 and 24 are threaded within openings in the members 21 and 22 respectively and are in absolute alignment with each other. The members 23 and 24 carry the lock units 25 and 26 respectively.

A revoluble device comprises the annular member 27 carrying the two plugs 28, 29, each of which has a conical recess into 70 which the pointed ends of the members 23 and 24 may be inserted to act as revoluble points for the member 27.

A threaded bolt 30 is screwed into the member 27, the exterior threads upon the head of which thread with the interior threads of the tubes 31. Threaded upon the exterior threads of the tube 31 is a ball 32, having an extended opening into which is inserted the tube 33, having a cap 34, which is maintained in position by the threaded rod 35. A ball 36 is movable within the tube 33, and a nut 37 is threaded upon the member 35.

A similar tube 31', containing a similar tube and ball, a similar ball 32' with threaded member 35' and nut 37' are similarly attached to the member 27.

Screwed into the member 27 is a thermometer holder 38, carrying the thermometer 39, 90 the lower portion of the holder 38 having the threaded member 40 carrying the nut 41.

The tubes 31 and 31' and the thermometer holder 38 are preferably placed equidistant from each other upon the member 27. 95

Fixedly attached to the side 11, and separated therefrom, by the insulating material 52, is an electric conductable supporting member 42. The member 42 carries the electric conductable member 43 and is separated 100 therefrom by the insulating material 44. The member 43 carries the two free swinging arms 45 and 45', the lower ends of which carry the members 46 and 46' respectively. The wire 47, attached to the member 42, and the wire 48, attached to the member 43, pass outwardly from the box through the insulated member 49 and are connected to the

battery 50 and the electrically actuated bell 51. It is evident, therefore, that if the member 46, or the member 46', be brought into contact with the member 42, the electric circuit will be completed and the alarm bell sounded.

The mode of the application and method of use of my illustrated device is as follows:

The device, as shown, particularly in Figure 1, is in a position where one of the axial lines A, A, A is in an absolutely vertical position. The front glass door is opened and the device moved into the position shown by the axial lines B, B, B in which the previously vertical line has been moved out of its vertical position. The device is then balanced accurately in this position, which is accomplished by varying the position of the balls 32 and 32', the more delicate balancing being accomplished by means of the nuts 37, 37' and 41. When the device is in accurate balance, the door is closed and locked. The temperature of the surrounding air is transmitted through the openings 13, 13, 13 of the device and affects the mercury in the thermometer 39. A raise in temperature will cause the mercury to rise in the thermometer destroying the equilibrium and causing the device to rotate upon its pivotal point in the direction of the arrow in Figure 1, the rotation being facilitated by the ball within the tube 31' rolling toward the ball 32'. The rotation of the device will bring the tube 31 against the member 46, causing it to abut upon the member 42, as shown in Figure 3, thus completing the electric circuit and sounding the bell alarm 51, which position will be maintained until the device is manually revolved to release the member 46 from its abutment upon the member 42.

A reverse rotation of the device can be obtained by balancing the device upon axial lines upon the opposite side of the vertical axial line A, in which case the circuit will be completed by the abutment of the tube 31' upon the member 46' and of the latter upon the member 42.

It will thus be seen that the device of my invention discloses means whereby a raise of temperature will react through the medium of a thermometer to sound an alarm.

I do not limit myself to the particular size, shape, number or arrangement of parts as shown and described, all of which may be varied without going beyond the scope of my invention as shown, described and claimed.

What I claim is:

1. In a device of the character specified, in combination, a casing, a pivotal member within the casing, a plurality of arms carried by the pivotal member, means for balancing the arms in a non-vertical position, a thermometer carried by one of the arms and means whereby an increase in temperature will cause the liquid within the thermometer to revolve the arms completing an electric circuit and sounding an alarm.

2. In a device of the character specified, in combination, a casing, a pivotal member within the casing, a plurality of arms carried by the pivotal member, a removable weight carried by each arm, a thermometer carried by one of the arms and means whereby an increase in temperature will cause the liquid within the thermometer to revolve the arms completing an electric circuit and sounding an alarm.

3. In a device of the character specified, in combination, a casing, a pivotal member within the casing, a plurality of tubes carried by the pivotal member, means for balancing the tubes in a non-vertical position, a thermometer within one of the tubes, means whereby the rise of the liquid will revolve the tubes completing an electric circuit and sounding an alarm.

4. In a device of the character specified, in combination, a casing, a pivotal member within the casing, a plurality of tubes carried by the pivotal member, a movable weight carried by each tube, means for maintaining each weight at any predetermined position upon its tube, a thermometer within one of the tubes and means whereby the rise of the liquid will revolve the tubes completing an electric circuit and sounding an alarm.

5. In a device of the character specified, in combination, a casing, a pivotal member within the casing, a plurality of tubes carried by the pivotal member, a movable weight carried by each tube, means for maintaining each weight at any predetermined position upon its tube, a movable ball within at least one tube, a thermometer within one of the tubes and means whereby the rise of the liquid will revolve the tubes completing an electric circuit and sounding an alarm.

Signed at New York city, in the county of New York and State of New York, this 5th day of February, 1921.

SILVIO MAGATON.
